SPRAY NOZZLE

John U. Béte, Stoughton, Mass., assignor to Béte
Fog Nozzle, Inc., Greenfield, Mass., a corpora-
tion of Massachusetts

Application April 6, 1951, Serial No. 219,549

6 Claims. (Cl. 299—121)

1

This invention relates to spray type nozzles and is directed particularly to a spray nozzle for fire prevention and fire extinguishing purposes, of the type shown in my patent No. 2,518,116 entitled "Spiral Film Spray Nozzle" issued on August 8, 1950.

The object of this invention is to provide a spray type nozzle that has a solid cone shaped spray.

Another object of the invention is to provide a spray nozzle that has a predetermined axial component combined with an effective spreading action.

Another object of the invention is to provide an elongated nozzle that has an even distribution of a high rate flow and is strong and rugged in construction.

Other and further objects of the invention, particularly in the tapering of the nozzle structure to a narrow tip at the end, will appear from the following description taken in connection with the accompanying drawings in which

Fig. 1 is a side view of the nozzle;

Fig. 2 is a longitudinal sectional view of the nozzle taken through the center of the nozzle;

Fig. 3 is a fragmentary view of the lower end of the nozzle;

Fig. 4 is an enlarged cross sectional view of the upper portion of the vane; and

Fig. 5 is a cross sectional view of the lower portion of the vane.

The nozzle shown in the drawings is of a generally tubular shape with a central passage 10 for passing the liquid from the inlet orifice 11 to the helical slot 12 between the convolutions of the helically formed vane 13 on the lower part of the nozzle. A needle-shaped core 14 is positioned in the lower portion of the passage 10 within the vane 13 widening in the direction of flow of the liquid to progressively reduce the cross sectional area of the passage 10 and force the liquid jet to expand against the inner cutting edge of the vane 13. The vane 13 has an active surface 15 substantially lateral to the direction of flow of the liquid and adjacent the passage 10. The active surface 15 peels off the liquid and disperses it as a substantially uniform spray outside the nozzle through the slot 12 between the convolutions of the vane. The vane 13 is shaped on the general form of a helix around the cylindrical exit passage portion 18 of the passage 10 with the convolutions of the vane spaced from one another to form the helical slot 16 in communication with the exit passage portion 18 through the helical opening 19 in the wall 20. The passage 10 may have a venturi 17 narrowing in the direction of flow to increase the velocity of flow of the liquid in the exit passage portion 18 impinging on the inner edge of the active surface 15 of the vane 13. The winding of vane 13 starts at a point above the narrowed end of the venturi 17 and terminates at the lower end of the nozzle. The vane 13 comprises an upper portion having a cross sec-

tional shape as indicated in Fig. 4 and a lower portion having a cross sectional shape typified in Fig. 5.

The upper portion of the vane 13 comprises the convolutions 23, 24, 25 with the cross section of the convolution 24 shown in an enlarged view in Fig. 4. Considering the cross sectional shape, the outer wall 28 is tapered narrowing the core end of the nozzle. The active surface 15 is substantially lateral to the flow of the liquid and is at a small angle to a plane lateral to the axis of the nozzle. The surface 15 forms a sharp edge 30 with the wall 31 of the passage 18. The outer portion 32 of the vane is stepped so that the surface 33 is recessed below the surface 15. An outer portion of the stream or jet of liquid flares and catches on the edge 30 and surface 15 and is directed outwardly through the slot 12 as a sheet or mass of water that disintegrates into droplets of a spray. The recessed surface opens the slot 12 and forms a discontinuity in the surface of the vane. The step 34 between the surfaces 15 and surfaces 28 is cut under slightly adjacent the outer surface 28. The surface 36 is concave and has a sharp concave portion 37 adjacent the passage 18 and shallow concave portion 38 extending outwardly to the wall 28.

The lower vane portion has an active surface portion 15a that is at a large angle to a plane lateral to the axis of the nozzle and directs the liquid flow so that the spray has a substantial axial component. The thin edge 40 between the surface 15a and the wall 31 narrows down to a sharp edge on the latter part of the convolution 26 and the convolution 27 bringing the upper portion of the surface 15a close to the surface 41 of the core 14. The under surface 42 is similar in shape to the under surface 36 except that the surface adjacent the outer edge 44 is flattened.

In Fig. 3 the change-over from the upper portion of the vane to the lower portion is shown. The step 34 terminates and the active surface is longer, extending out to the edge of the vane. A small portion 40 of the surface 15 extends onto the lower portion for a short circumferential distance and then turns into a sharp edge.

The core 14 has a tapered surface 43 terminating in a point 46 and a cylindrical surface 47 snugly fitting the end of the passage 18 and engaging the wall 31. An axial pressure bearing pin 48 projects from the core 14 and engages a notch 49 at the end of the vane 13 to hold the core in the nozzle. The pin is inserted into the slot 12 through the slot 51 and then turned to set in the notch 49. The core is securely held in place by the nut 52 tightened on the threads 53 and seated against the flat end 54 of the nozzle.

The venturi 17 extends down to the exit passage portion 18 and merges with it to form a continuous smooth surface. The vane 13 starts at the lower portion of the venturi with the edge 30a of the convolution 23 in the surface of the venturi 17 so that the inner surface 31a of the convolu-

tion is slightly tapered or narrowing in the direction of the flow. The edge 30a is positioned inwardly toward the axis of passage 10 and projects inwardly from the opposing edge 35 exposing the edge 30a to the flow of liquid. The edge 30a and surface 15 peel off an outer portion of the moving liquid and direct it outwardly.

The core 14 extends into the passage up to within in the convolution 24 with the point 46 on a level with the upper portion of the edge 30b of the convolution 24. The portion of the surface 31 forming the passage 18 is substantially cylindrical and the cross sectional area of the passage 18 is reduced by the widening conical-like surface 43 and the helical space between the surface 43 of the core and the helical surface 31 is reduced progressively. The longitudinal space in the direction of axial flow is reduced longitudinally so that liquid entering at the wide end has an increased velocity or is maintained at substantially the same velocity as on entering the passage 18.

The active surface is preferably helically formed with the surface substantially equal for each convolution.

The walls of the nozzle are thick and made preferably of brass or stainless steel. The vane 13 at the portion adjacent the venturi has walls as thick as the walls of the Venturi section. The outer surfaces of the nozzle are tapered inwardly reducing the thickness of the walls of the nozzle and the obstruction of the outer supporting portion 32 to remove any interference of the support with the dispersion of the liquid.

The liquid enters at the orifice 11 under pressure from a supply into the venturi 17. The venturi 17 reduces the cross sectional area of the flow increasing the velocity of the liquid while still within the tapering walls of the venturi and impinges on the edge 30a and surface 15 projecting into the liquid and forming a discontinuity in the wall of the passage. The edge 30a and surface 15 of the convolution 23 shave off a sheet of liquid and disperse it outwardly around the nozzle at an acute angle to a plane lateral to the axis of the nozzle in the general shape of a cone. The liquid moves on to within the walls 31 of the convolution 24. The core 14 acts on the liquid forcing it outwards against the edge 30 of the vane 13, maintaining the passage 18 filled with liquid moving at a high velocity. The edge 30 and surface 15 of the successive convolutions shave off a portion of the liquid and disperse it outwardly at an angle around the nozzle filling in the cone of spray. The shape of the vane 13 changes on convolutions 26, 27 and the surface 15a is at a greater angle and directs the liquid in a more axial direction to fill in the center of the cone of spray and form a solid mass of saturating spray. The sheets of liquid start to break up after leaving the surface 15 and eventually disintegrate into droplets forming a spray and an atmosphere diffused with liquid droplets.

While a particular embodiment of the invention has been shown and described, it is understood that various changes and modifications can be made without departing from the invention.

I claim:

1. A nozzle for producing a spray of desired characteristics directed outwardly around an axis comprising a generally tubular member having a passage to form a liquid jet around said axis, a core member coaxial with said tubular member and positioned centrally in said jet and tapered to divert the jet flow progressively outward in annular formation around said core member and

a single vane winding helically around said annular jet and having a relatively narrow helical slot of smaller axial width than the axial thickness of said vane and with an active surface of said vane inclined outwardly at an angle to said axis with its inner edge spaced progressively nearer to the surface of said tapering core, the angle of said active surface becoming greater at the core end of the nozzle so that as the jet is progressively spread outwardly by said core a portion engages the active surface with the greater angle and is peeled off the jet and diverted outwardly by the active surface to form a full cone-shaped spray.

15 2. A nozzle for producing a cone-shaped spray around an axis comprising a generally tubular member having a central passage to confine a liquid stream around said axis, a venturi at the inlet end of said passage, a helical vane formed around said stream overlapping with the venturi to taper the inner wall of said vane and position the inner edge of said vane in said stream of liquid to divert said liquid outside of said nozzle, and a core member coaxial with said tubular member and positioned within said vane to narrow the cross sectional area of said passage beyond said venturi and force the stream of liquid outwardly against said inner edge of said vane to further disperse said stream and form a substantially full cone-shaped spray.

3. A nozzle for producing a cone-shaped spray around the axis of the nozzle comprising a generally tubular member having an inner surface to form a passage to axially confine a solid stream of liquid, a vane formed helically around said stream and having a surface inclined outwardly at an angle to said axis, said inner surface formed into a velocity-increasing venturi at the inlet end overlapping with the active surface of said vane to position said active surface in said stream from said wall to disperse a portion of the stream outwardly at an angle to said axis and around said nozzle, a tapered core coaxial with said tubular member and positioned within said vane beyond said overlapping portion of said venturi and said surface to force said stream against said active surface to disperse said liquid in a cone shape, and a second active surface on the core end of said vane at a large angle to a plane lateral to said axis to disperse said stream in a cone shape with a substantial axial component to fill said cone spray.

4. A nozzle as claimed in claim 1 wherein the angle of said active surface changes abruptly and said active surface having the greater angle has a longer radial dimension than the active surface at the smaller angle.

5. A nozzle as claimed in claim 1 wherein said vane has an outer surface tapering inwardly to widen the space between the convolutions of the vane so the dispersed liquid can be directed with a larger axial component.

6. A nozzle as claimed in claim 1 wherein the outer surface of the helical vane tapers continuously from a large diameter at its base to a substantially smaller diameter at its tip.
